ATTORNEY.

FIG. 3.

UNITED STATES PATENT OFFICE.

FRANK MAGAZINER, OF SPRINGFIELD, MASSACHUSETTS.

BREAD-ROLL PRESS.

Application filed July 18, 1925. Serial No. 44,413.

This invention relates to improvements in devices for flattening or compressing bread rolls, and its leading object is to provide a device of this character with a presser board which will cover a tray or pan of rolls, and to also provide an automatic balancing lever system, whereby the presser board will return to elevated position when manual pressure on the lever system is removed.

10 A further object of the invention is the provision of a device of this character with a presser board comprising two sections, one of which is adapted for use on a tray and the other of which is adapted for use on a pan.

15 A still further object of the invention is the provision of a device of this character with a tray supporting table, with a sliding support for supporting a loaded tray or pan, when the pressed rolls are withdrawn from the device.

20 With the above and other objects in view the invention consists in certain new and useful combinations, constructions, and arrangements of parts, clearly described in the following specification and fully illustrated in the accompanying drawings, in which:—

25 Fig. 1 is a side elevation, showing the presser board in its compressing position, with dotted lines showing of the presser board in its elevated position.

30 Fig. 2 is a plan view thereof.

Fig. 3 is a cross sectional view of the presser board.

35 Referring to the accompanying drawings illustrating the practical embodiment of my invention 5 designates a table, which is supported upon the legs 6, suitably braced by the horizontal braces or rungs 7. This stand or support may be made of any material, angle steel or otherwise, as of wood or tubular metal.

40 The sides of the table 5 are provided with side boards 8 and 9, located on opposite sides thereof, and which rise above the horizontal plane of the table. An end wall 10 is also provided, while the front portion of the table is normally open to admit the tray or pan containing the bread rolls to be flattened or pressed.

45 Against the end wall 10 vertical angle members 11 and 12 are rigidly mounted, and their upper ends extend above the upper horizontal edge portion of the end wall and to these upper ends the operating levers 13

and 14 are pivotally connected by means of the shaft 15, which acts as a tie rod for holding the members 11 and 12 in fixed spaced relation to each other. The shaft 15 extends through the levers at points nearer the rear ends of the levers, thus providing short rear arms 15^a and long forward arms 15^b. The forward terminals of the levers are connected together by a tie rod 16, which forms an operating handle for the manipulation of the twin levers, and which is supported a considerable relative distance forwardly of the front edge of the table 5, so that the workman may apply the weight of his body to the levers for operating the device. 70

75 The forward lever arms are pivotally connected to the pendant hangers 17 and 18, which are rigidly bolted or secured to the presser board section 19. The hangers are pivoted on the levers by the pivots 20 so that the presser board will occupy a horizontal position and may be swung into and out of the compartment defined by the sides and end wall of the table.

To the presser board section 19 the presser board section 21 is slidably and detachably secured, by the dovetailed jointing 22, so that the two boards will work as one, when so coupled or united to each other. The lower and larger presser board is used for 80 pressing rolls in trays, and the upper and smaller presser board is used for pressing rolls in pans. When it is desired to employ the device for pressing rolls in pans the lower section is detached from the upper 85 section. Each section is covered with cloth or other fabric covering, so that dough will not adhere thereto. 90

The presser bar is balanced by means of a weight 23 arranged on the short arms of the levers, and this weight is designed to exert sufficient pressure to maintain the presser board normally elevated when no manual pressure is being exerted on the handle. 95

100 The weights may be adjusted on the levers by means of the clamping bolts 24, which extend through the weights, the weights being slotted to receive the levers, and the bolts serving to clamp the walls of the slotted portions against the levers.

105 A support for the tray or pan when being withdrawn from the table is provided which preferably comprises a U shaped frame 25 which has its parallel side portions slidable 110

in guides 26 and 27, secured to the underside of the table 5. Stops 25' at the ends of the side portions are arranged to abut the stops 26 to limit the outward movement of the support as shown in the drawings.

The pan to contain the rolls, or the tray, as the case may be, is placed on the table and the rolls then transferred to the pan or tray. When the pan or tray has been filled 10 or fully loaded with rolls in a single horizontal layer, the workman grasps the operating handle of the presser levers and applies his weight to force the presser board into compressing position against the rolls. As 15 the levers swing from the extreme upward positions to their compressing positions, the presser board will swing directly on the rolls, its lower surface remaining in a balanced horizontal plane so that uniform pressure 20 will be applied to the rolls, when the presser board is forced into snug engagement therewith.

The workman may apply any suitable degree of manually exerted pressure, so that 25 any required degree of flatness of the rolls may be accomplished.

Upright guides 28 and 29 are located against the end wall of the table, and on these guides the inclined members 28' and 30 29' are provided, for protecting the end wall against the swinging motion of the presser board. The pressure board is designed to swing directly into the tray or pan, which

is arranged on the table in such manner that this will be permitted.

Having described my invention I claim:—

1. A roll pressing device comprising in combination, a table having a rear wall and side walls extending upwardly therefrom, spaced levers pivoted at one end to the rear wall of said table, a cross bar fixed in the opposite end of said levers, a bar fixed to said levers intermediate the ends thereof, a presser member pivoted on said last named cross bar and depending therefrom, guides fixed on the rear wall adjacent said table arranged to engage the rear side of said presser member for guiding it as it approaches said table.

2. A device of the class described comprising in combination, a table having a rear wall and side walls extending upwardly therefrom, spaced levers pivoted adjacent their ends to said rear wall, a cross bar fixed to the other end of said levers, a presser member over said table pivoted to and depending from said levers intermediate the ends thereof, guides fixed on said rear wall adjacent said table for engaging the rear side of said presser member for guiding it as it approaches said table and counter balances adjustable on the ends of said levers outside the said rear wall.

In testimony whereof I affix my signature.

FRANK MAGAZINER.
